CUP-Saucer ASH TRAY COMBINATION

James Wiley Stampley, Olivehurst, Calif.
(129 Swaab St., Las Vegas, Nev. 89110)

Filed Apr. 17, 1973, Ser. No. 351,858

Term of patent 14 years

Int. Cl. D7—01

U.S. Cl. D7—3

FIG. 1.

FIG. 2.

FIG. 3.

FIG. 4.

FIG. 5.

FIG. 6.

FIG. 1 is a top perspective view of a cup-saucer ash tray combination showing my new design;

FIG. 2 is a side view thereof;

FIG. 3 is a plan view thereof;

FIG. 4 is an end view;

FIG. 5 is a side view; and

FIG. 6 is an end view looking in the opposite direction from FIG. 4.

I claim:

The ornamental design for a cup-saucer ash tray combination, substantially as shown.
